UNITED STATES PATENT OFFICE.

WILLIAM H. ELMER, OF BERLIN, WISCONSIN.

TURBINE WATER-WHEEL.

SPECIFICATION forming part of Letters Patent No. 314,171, dated March 17, 1885.

Application filed January 8, 1885. (No model.)

To all whom it may concern:

Be it known that I, WILLIAM H. ELMER, a citizen of the United States, residing at Berlin, in the county of Green Lake and State of Wisconsin, have invented certain new and useful Improvements in Turbine Water-Wheels, of which the following is a specification, reference being had therein to the accompanying drawings.

10 My invention relates to improvements in turbine wheels, and is designed to produce an easily-operated and efficient gate for admitting water or preventing the passage thereof to the wheel proper.

15 The invention is fully set forth in the following description, reference being had to the annexed drawings, in which—

Figure 1 represents a plan view of a portion of the wheel; Fig. 2, a horizontal section 20 through the same, and Fig. 3 a detail perspective of the gate-operating mechanism.

The wheel is of any approved construction, and is journaled within a suitable casing, which is provided with tangent openings. 25 The gates are formed of two disks, A, with a side connection, B, and rest in cylindrical bearings in the casing. The connections B are of sufficient width to close the opening in the casing when properly placed.

30 To the exterior surface of the top disk A is secured a block, C, having a continuation, D, provided with a slot, E. The block C carries a rod, F, on which fits loosely enough to travel thereon a block, G. This block has a 35 rod or continuation, H, which rests in a perforation or bearing in a plate or disk, I. The

gates having been adjusted to the block C by means of the slotted continuation D, through which a portion of the securing devices pass, and the blocks G pivotally set in the disk I, 40 which rests on them, it is evident that turning the said disk I for a distance will cause the gates to turn in their bearings sufficiently to open or close the orifices in the casing.

What I claim is—

1. In a turbine water-wheel, a gate-operating device consisting of a block connected to the gate and having a rod continuation, a partially-rotating disk or plate, and a block pivoted to the same and traveling on the said 50 rod, substantially as and for the purpose specified.

2. In a turbine wheel, a gate-operating device consisting of a block with a slotted continuation and a rod, a plate or disk partially 55 rotating, and a block pivoted to said plate and traveling on the rod, substantially as and for the purpose specified.

3. The combination, with the gates and partially-rotating disk or plate of a turbine wheel, 60 of a block or blocks adjustably secured to the gates and having a rod-extension, and a block pivoted to the said disk or plate and traveling on the said rod-extension, substantially as and for the purpose specified.

65 In testimony whereof I affix my signature in presence of two witnesses.

WILLIAM H. ELMER.
